UNITED STATES PATENT OFFICE.

HARRY A. GRAMMES, OF ALLENTOWN, PENNSYLVANIA.

DESIGN FOR A METAL PAPER FASTENER OR CLIP.

51,263.

Specification for Design.

Patented Sept. 11, 1917.

Application filed June 20, 1917. Serial No. 175,832. Term of patent 3½ years.

To all whom it may concern:

Be it known that I, HARRY A. GRAMMES, a citizen of the United States of America, residing at Allentown, in the county of Lehigh and State of Pennsylvania, have invented a new, original, and ornamental Design for Metal Paper Fasteners or Clips, of which the following is a specification, reference being had to the accompanying drawing, forming a part thereof.

The figure is a perspective view of a metal

paper fastener or clip, showing my new design.

I claim:

The ornamental design for a metal paper fastener or clip, as shown.

In testimony whereof I affix my signature in presence of two witnesses.

HARRY A. GRAMMES.

Witnesses:

HARRY F. SMITH,
EDWIN A. EYER.
